C. Snow, Jr.

Inventor

Sheridan J. Myers

UNITED STATES PATENT OFFICE.

SHERIDAN J. MYERS, OF HEBRON, MISSISSIPPI.

REIN-SUPPORT.

SPECIFICATION forming part of Letters Patent No. 475,465, dated May 24, 1892.

Application filed December 7, 1891. Serial No. 414,319. (No model.)

To all whom it may concern:

Be it known that I, SHERIDAN J. MYERS, a citizen of the United States, residing at Hebron, in the county of Lawrence and State of Mississippi, have invented a new and useful Line-Holder and Trace-Guide, of which the following is a specification.

This invention relates to improvements in line holders or guides to be used in plowing; 10 and the objects in view are to provide a cheap and simple device that may be readily attached and detached to and from or adjusted along the trace-chains of a plow-harness and is adapted to support the lines and prevent the 15 same from rubbing and wearing away.

Other objects and advantages of the invention will appear in the following description, and the novel features thereof will be particularly pointed out in the claims.

20 Referring to the drawings, Figure 1 is a perspective in detail of a combined rein guide and support constructed in accordance with my invention. Fig. 2 is a vertical longitudinal section of the device, the same being in 25 position upon a trace-chain.

Like numerals of reference indicate like parts in all the figures of the drawings.

In practicing my invention I prefer to cast the guide-frame, and the same consists in a 30 diamond-shaped loop 1, from which depend opposite parallel arms or hangers 2. The hangers are provided at their lower ends with bearing-perforations 3, which receive a pin 4, upon which is mounted for rotation a concaved 35 roller 5. Above the bearing-openings 3 bearing-slots 6 are formed in the hangers and the same receive the trunnions 7, formed upon a concaved roller 8, located above the said roller 5. The upper end of the guide-frame is provided 40 with a transverse slot 9, and the lower end of the diamond-shaped loop 1 is provided with a perforation 10, vertically below the slot 9. In the slot and perforation thus formed a pin 10^a, the upper end of which is provided 45 with a head 11, is removably mounted. The pin has one of its faces provided with a groove 12, and in the same lies the tail end of a spring-catch 13, the lower end of which is secured to the pin and the shoulder of which engages 50 with the under side of the diamond-shaped loop, whereby the pin is prevented from ac-

idental disengagement, but is capable of being disengaged and withdrawn by a compression of the spring-catch against or into the pin.

14 designates a portion of an ordinary chain-trace, consisting, as is usual, of the series of links. In the application of the device the chain is passed through the diamond-shaped loop and the device slid to a point between the hames and back-strap, after which the 55 pin is inserted, so as to engage with or pass through a convenient link, and thus the device becomes locked at the desired point upon the chain. The lines or reins are now passed through the guide between the concaved rollers, and, while freely sliding therein without wear, are maintained or guided in position. By reason of the movability vertically of the upper roller the end of the lines usually buckled together or knotted may be readily 60 passed through the device, and after such passage the upper roller will return to its position, accommodating itself and the distance between the rollers to the thickness of the 65 lines.

70 From the foregoing description, in connection with the accompanying drawings, it will be seen I have provided a device of great simplicity and cheapness that is readily attached and detached to the trace-chains of 75 heavy draft-harness ordinarily employed for plowing.

Having described my invention, what I claim is—

1. The herein-described rein-support, the 80 same consisting of the upper trace-chain-receiving eye, adapted to be supported on the trace-chain and having a locking-bolt for engaging one of the links of the chain, a rein-supporting loop or frame depending from the 85 eye, and rollers located in the loop or frame, substantially as specified.

2. The herein-described combined rein guide and support, the same consisting of the chain-receiving loop and means for securing 90 the chain therein, the depending hangers having bearing-perforations near their lower ends and above the same provided with slots, and rollers mounted in the perforations and slots, substantially as specified.

100 3. The herein-described combined rein guide and support, the same consisting of the

diamond-shaped loop having vertically-opposite openings, the trace-engaging bolt mounted therein, the spring-shoulder mounted on the bolt and adapted to engage the eye, hang-
5 ers depending from the eye and provided with bearings, and rollers mounted in the bearings, substantially as specified.

In testimony that I claim the foregoing as my own I have hereto affixed my signature in the presence of two witnesses.

SHERIDAN J. MYERS.
